(57) **CLAIM**

The ornamental design for a seat, as shown and described.

DESCRIPTION

FIG. 1 is a perspective view of a seat in accordance with the new design;

FIG. 2 is a front elevational view thereof;

FIG. 3 is a left side elevational view thereof, a right side elevational view being a mirror image thereof;

FIG. 4 is a rear elevational view thereof;

FIG. 5 is a top view thereof;

FIG. 6 is a bottom view thereof;

FIG. 7 is a perspective view similar to FIG. 1 with the seat in position on a first stool support;

FIG. 8 is a front elevational view similar to FIG. 2 with the seat in position on the first stool support;

FIG. 9 is a left side elevational view similar to FIG. 3 with the seat in position on the first stool support, a right side elevational view being a mirror image similar to FIG. 3 with the seat in position on the first stool support;

FIG. 10 is a rear elevational view similar to FIG. 4 with the seat in position on the first stool support;

FIG. 11 is a top view similar to FIG. 5 with the seat in position on the first stool support;

FIG. 12 is a bottom view similar to FIG. 6 with the seat in position on the first stool support;

FIG. 13 is a perspective view similar to FIG. 1 with the seat in position on a second stool support;

FIG. 14 is a front elevational view similar to FIG. 2 with the seat in position on the second stool support;

FIG. 15 is a left side elevational view similar to FIG. 3 with the seat in position on the second stool support, a right side elevational view being a mirror image similar to FIG. 3 with the seat in position on the second stool support;

FIG. 16 is a rear elevational view similar to FIG. 4 with the seat in position on the second stool support; FIG. 17 is a top view similar to FIG. 5 with the seat in position on the second stool support;

FIG. 18 is a bottom view similar to FIG. 6 with the seat in position on the second stool support;

FIG. 19 is a bottom perspective view of the seat of FIGS. 1-6; and,

FIG. 20 is another bottom perspective view of the seat of FIGS. 1-6.

The broken lines in the drawings illustrate portions of the seat which form no part of the claimed invention.

1 Claim, 14 Drawing Sheets
